UNITED STATES PATENT OFFICE.

THOMAS BROADBENT, OF SCHENECTADY, NEW YORK.

CASTING APPARATUS.

1,291,390.

Specification of Letters Patent. Patented Jan. 14, 1919.

Application filed February 28, 1918. Serial No. 219,665.

To all whom it may concern:

Be it known that I, THOMAS BROADBENT, a citizen of the United States, and a resident of Schenectady, in the county of Schenectady 5 and State of New York, have invented a new and Improved Casting Apparatus, of which the following is a full, clear, and exact description.

The object of the invention is to provide a 10 new and improved casting apparatus, more especially designed for casting a plurality of rings or other articles at one operation in a single flask. Another object is to permit casting of rings of different diameters at one 15 operation. Another object is to produce cast articles which are exceedingly clean and homogeneous. Another object is to dispense with the employment of a skilled molder.

In order to produce the desired result, use 20 is made of a series of dry sand molds and a dry sand distributing member common to all the molds to supply the latter simultaneously with the molten metal and to allow escape of air from the molds.

25 A practical embodiment of the invention is represented in the accompanying drawings forming a part of this specification, in which similar characters of reference indicate corresponding parts in all the views.

30 Figure 1 is a perspective view of the casting apparatus;

Fig. 2 is a cross section of the same;

Fig. 3 is a longitudinal central section of the same;

35 Fig. 4 is a side elevation of a number of the rings cast;

Fig. 5 is a plan view of one of the dry sand molds;

40 Fig. 6 is a sectional side elevation of a modified form of a series of dry sand molds; and

Fig. 7 is a similar view of another modified form of a series of dry sand molds.

The flask 10 of the casting apparatus illustrated in the drawings is circular and provided at the ends with flanges 11 and 12 to which are secured covers 13 and 14 by the use of bolts 15 and 16 or other suitable fastening devices. Each of the covers 13 and

50 14 is provided with lifting lugs 17 and with strengthening ribs 18 to reinforce the covers. A hollow conical member 20 connects the covers 13 and 14 with each other at the middle by the use of suitable bolts 21 and 22, as

55 plainly illustrated in Fig. 3.

The flask 10 contains green sand 30 in

which is embedded a series of molds 31, each made of dry sand, in one piece or in segments, or in sections according to size and shape, and arranged one alongside the other 60 and flanked by dry sand end members 32, 33. Each of the molds 31 shown in Fig. 3 is provided on its face with a recess 34 corresponding to the shape of the article to be cast. As shown, for instance, in Figs. 2 and 65 3, the recess 34 of each mold is formed of two concentric rings to permit of casting two rings of different diameters, but I do not limit myself to the number of such ring-shaped recesses or to the shape of the recesses 70 described as the same can be varied according to the shape of the article to be cast. When the recess 34 is formed of two ring-shaped recesses then such ring-shaped recesses are connected with each other by gate 75 recesses 35 to allow the molten metal to pass from the outer recess to the next following one. The recesses are also connected with each other by a riser recess 36 and each mold is also provided on the top with a gate 80 opening 37 and a riser opening 38. As illustrated in Figs. 6 and 7 each mold 31 is provided on each face with an annular recess 34, the registering recesses of adjacent molds corresponding to the cross section of the ring 85 to be cast. It is expressly understood that the cross section of the recesses is varied according to the desired cross section of the rings to be cast.

The top of each mold 31 is provided with 90 a flat face 40 and on the faces of the several molds 31 is set a runner box 41 extending through an opening in the top of the flask 10. The runner box 41 is provided with two openings 42 and 43, of which the opening 42 95 connects with the several gate openings 37 while the opening 43 connects with the several riser openings 38. The runner box 41 is preferably made in two parts separated by a metal plate 44. The runner box 41 may 100 be made of green sand and in this case core blocks are set on the face 40 over the gate openings 37 and riser openings 38, after which green sand is rammed around the blocks and then the latter are withdrawn. 105

It will be noticed that molten metal poured into the gate opening 42 is distributed to the several gate openings 37 of the several molds 31 so that molten metal simultaneously flows into the recesses 34 of all the molds 31 contained in the flask, whereby a corresponding number of articles 50 (see Fig. 4) are cast 110

simultaneously. It is understood that the air in the recesses can escape by way of the riser openings 36, 38 and 43, to insure the proper filling of the recesses with the molten metal.

The top of the flask 10 is provided with upwardly extending flanges 60, on which are adjustably secured vertically movable flanges 61 by the use of bolts 62 held in the flanges 60 and extending through slots 63 formed in the flanges 61. The flanges 61 fit on opposite sides of the runner box 41 and extend downward to the peripheral edges of the several molds 31 adjacent the sides of the seat 40 to hold the molds against accidental shifting and thereby holding the openings 37, 42 and 38, 43 in proper register.

In using the casting apparatus the flask 10 is set up on end, preferably at the cover 13, and then a quantity of green sand is placed in the flask, after which the covering member 32 is placed in position on the green sand and additional green sand is added and rammed to hold the end member in place. The first mold 31 is now placed on top of the end member 32 and additional green sand is added and rammed to hold this mold in place, after which another mold is placed in position on the first mold, and the above described operation is repeated until all the molds and the last end member 33 are in place, and a final layer of green sand is placed into the upper end of the flask, after which the cover 14 is fastened in position on the flask, or the covering member and any number of the molds may be placed in position before ramming, it not being necessary to ram each mold or core separately. The flask is now turned over into the position shown in the drawings and then the runner box 41 is provided, as previously explained. The casting apparatus is now ready for receiving the molten metal.

To insure proper placing of the end members 32, 33 and the molds 31, use is preferably made of a suitable templet inserted between the wall of the flask 10 and the outer edges of the said end members and molds to properly space the same from the wall of the flask 10. Care has also to be taken that the seats 40 of the several molds are in alinement, it being understood that for this purpose the flanges 61 form proper guiding means.

The central member 20 is used to save green sand especially on castings of large diameters. On small work or bench work the central member need not be used and in this case a bolt is used extending from plate to plate to hold the flask from straining.

Having thus described my invention, I claim as new and desire to secure by Letters Patent:—

1. A casting apparatus, comprising a flask containing green sand a series of dry sand

molds embedded in the green sand and arranged one alongside the other to form between them a recess corresponding to the article or section of the article to be cast, dry sand end members arranged alongside the end molds, and a runner box in communication with the recesses of the several molds.

2. A casting apparatus, comprising a flask containing green sand, a series of dry sand molds embedded in the said green sand and arranged one alongside the other, each mold being provided in a face with a recess corresponding to the article or a section of the article to be cast and covered by the back of the adjacent mold, a runner box in communication with the recesses of the several molds to simultaneously fill the recesses with molten metal poured into the runner box, and dry sand end members arranged alongside the end molds, one of the end members forming a cover for the recess in the adjacent end mold.

3. A casting apparatus, comprising a flask containing green sand, a series of dry sand molds embedded in the said green sand and arranged one alongside the other, each mold being provided in a face with a recess corresponding to the article or a section of the article to be cast and covered by the back of the adjacent mold, each mold being provided with a gate opening and a riser opening, the said openings leading to the corresponding recess, and a runner box within the flask on top of the molds and having a gate opening and a riser opening registering with the said openings in the molds.

4. A casting apparatus, comprising a flask containing green sand, a series of dry sand molds embedded in the sand and arranged one alongside of the other to form between them a plurality of concentric recesses corresponding to the articles, the recesses being connected by gate and riser openings, and a runner box on the molds and having gate and riser openings.

5. A casting apparatus, provided with a dry sand mold having a plurality of concentric recesses each corresponding to an article or a section of an article to be cast, gate and riser openings connecting the recesses with each other, and gate and riser openings leading from the outermost recess.

6. A casting apparatus, comprising a flask provided at the top with an opening, a plurality of molds arranged in the said flask one alongside the other and spaced from the walls of the flask, the said molds having alined raised seats at the top and each mold having in a face a recess corresponding to the article or a section of the article to be cast, the back of one mold forming a cover for the recess of the adjacent molds, each mold having gate and riser openings leading from the recess to the said seat, a run-

ner box set on the said seats and extending into the said top opening of the flask, and adjustable flanges held on the side walls of the said top opening of the flask and engaging the sides of the runner box and the peripheral edges of the molds adjacent the sides of the said seats.

7. A casting apparatus, comprising a flask provided at the top with an opening, a plurality of molds arranged in the said flask one alongside the other and spaced from the walls of the flask, the said molds having aligned raised seats at the top and each mold having in a face a recess corresponding to the article or a section of the article to be

cast, the back of one mold forming a cover 20 for the recess of the adjacent molds, each mold having gate and riser openings leading from the recess to the said seat, a runner box set on the said seats and extending into the said top opening of the flask, adjustable flanges held on the side walls of the said top opening of the flask and engaging the sides of the runner box and the peripheral edges of the molds adjacent the sides of the said seats, and green sand packed in 30 the said flask and around the said molds to the said flanges.

THOMAS BROADBENT.
